UNITED STATES PATENT OFFICE

2,365,367

DISHWASHER

George A. Vandercook, Jackson, Mich.

Application September 2, 1942, Serial No. 456,997

3 Claims. (Cl. 259—95)

The present invention relates to dishwashers and more particularly to a dishwasher, the washing action in which is obtained by the action of air intermittently admitted to the dishwasher through the bottom thereof in such a manner as to cause a surging movement of the washing liquids. The present invention is a continuation in part of my copending application, Serial No. 229,804, filed September 14, 1938.

Mechanical dishwashers have been known for some time. However, insofar as is known all prior mechanical machines have had the disadvantage that they have been too expensive to be within the reach of the ordinary housewife. Some of these dishwashers have employed air under pressure as the means for agitating the washing liquid. However, none of the prior art devices have employed the air under pressure in such a manner as to cause a surging of the liquid as distinguished from a simple agitation of the liquid.

An object of the present invention is to provide a compact, inexpensive, portable mechanical dishwasher.

Another object of the invention is to provide a mechanical dishwasher which may employ as a source of power a portable detached motor of general purpose use, such as the "Mix-Master" type.

Another object of the invention is to provide a dishwasher having a spring check valve in the bottom thereof for admitting air intermittently under pressure.

A further object of the invention is to provide a dishwasher into which the air is directed from the bottom thereof by air passing through a spring check valve and pumped by a reciprocating pump.

A still further object of the invention is to provide apparatus and a method for causing water in a container to surge due to the action of air entering the bottom in a predetermined manner.

The foregoing and other objects will be apparent from the following specification when taken with the accompanying drawing, in which

Fig. 1 is a partial vertical section of a dishwasher according to the present invention, and

Fig. 2 is a side elevation thereof showing the air pump with the cover plate removed.

Referring particularly to the drawing, the reference character 1 indicates a container made of sheet metal having a false bottom 2 to serve as a base, and a lid 3. The lid 3 is provided with an internal telescoping flange 4 for holding the

lid 3 in assembled relation with the container 1. The lid 3 is provided with a handle 5 having thereunder vents 6 and a baffle plate 7, shown particularly in Fig. 1, for permitting the escape of air which enters the container from the lower side thereof as will be hereinafter explained.

The container is provided with a rack 8 therein which rests on the bottom. The rack 8, which is not a part of the invention, is provided with a central compartment 9 for silverware and outer portions 10 for supporting dishes. A wire or the like framework 11 is arranged for securing the portions of the rack 8 together and to provide a means for conveniently withdrawing the same from the container 1.

At the center of the bottom of the container 1 is provided an air inlet 15 having thereon a check valve 16 which is loaded by a spring 17, the spring 17 having one end thereof secured to the check valve 16 and the other end thereof secured to the tube 18 communicating with the inlet 15. The valve 16 seats on the upper end of the air inlet 15. The tube 18 communicates with a reciprocating pump 19, the term reciprocating being used broadly, which preferably is secured to the side of the container 1. The pump 19 consists of a housing 20 having an outer cover plate 21. One side of the housing 20 constitutes a movable pumping member 21 which is pivoted about a pin 22 fixed with respect to the housing 20 in the container 1. The container has a housing 20 and an oscillatable side 21. Suitable packing may be provided to prevent the escape of air past the side 21. The side 21 is provided with an air check valve 23 and is oscillated by an eccentric 24 driven by a shaft 25. The eccentric 24 is operably connected to the side 21 by a connecting rod 26 pivoted to the side 21 by a pin 27. The shaft 25 of the eccentric 24 is driven by a speed reducing mechanism 28, not shown in detail, which is in turn driven by a rod 29 having a connecting end 30 at the top thereof to adapt the same to be driven by a removable portable motor such as of the "Mix-Master" type. A bracket 31 is provided for supporting the motor.

As the eccentric 24 is rotated, the side 21 is reciprocated pumping air outwardly through the outlet 35 into a conduit 36 which is connected to the conduit 18. The upper end of the conduit 18 is in the form of a goose neck 37 providing a trap for preventing the gravitation of washing liquid from within the container 1 into the pump 19.

The principal feature of the present invention is the way in which the air enters the container

1 through the air inlet 13 and the effect that it provides on the washing liquid therein. The air entering the container 1 through the inlet 13 is provided by the reciprocating pump 19, and as the result enters the container 1 intermittently. Furthermore the effect of the spring 17 is to hold back the passage of air into the container 1 until a predetermined pressure is built up and then to cause the valve 16 to suddenly release the air so that the entire charge of air enters the container substantially instantaneously. The effect of substantially instantaneously injecting the entire charge at one time under pressure is such to cause an explosion-like effect in the water and to impart to the water a surging action as distinguished from a mere agitation such as would be provided by a constant stream of air. It has been found that by providing any type of a pump which reciprocates and by spring loading the check valve to a sufficient degree to cause the entire charge of air to enter the container substantially instantaneously will produce the explosion-like effect described and cause the water to surge. By surging is meant that the sudden expanding of the air under pressure adjacent the bottom of the container causes a portion of the water to rise in the container and then fall back to replace the space taken by the air after the air rises to the top of the container. The action being repeated due to the intermittent operation of the pump causes an intermittent up and down movement or surging of the liquid which has a washing effect entirely absent when the washing liquid is merely agitated by a constant flow of air, no matter how violent the agitation is. Apparently the surging causes a large volume of water to continuously pass in

5 opposite directions over the surfaces being washed. This action has the result of carrying new washing liquids to the surfaces being washed and carrying away the film of washing liquid adjacent the surfaces being washed which has already been used.

10 From the foregoing specification it will be apparent that I need not be limited to the specific type of pump disclosed. Furthermore, it is contemplated that other means may be provided for supplying the air as described, than by a pump. Accordingly, I do not wish to be limited except by the scope of the following claims.

15 Having thus described my invention, what I desire to secure by Letters Patent and claim is:

- 15 1. A device of the character described comprising a liquid holding container having a bottom, a spring loaded check valve at said bottom and communicating with said container, means to intermittently supply air, and means providing a communication between said means and said valve whereby air is directed intermittently into said container through said valve to agitate the liquid in said container, the resistance to opening of the spring loaded valve and the means for intermittently supplying air being such as to cause each charge of air to enter the container substantially instantaneously whereby each charge of air has an explosion-like effect in the liquid to impart to the liquid a surging action.
- 20 2. The invention as defined in claim 1 wherein the check valve is adjacent the center of the bottom of the container.
- 25 3. The invention as defined in claim 1 wherein the air is supplied by a reciprocating pump.

GEORGE A. VANDERCOOK.
